UNITED STATES PATENT OFFICE.

GEORGE W. GOSS AND CHARLES E. GOSS, OF BALTIMORE, OHIO, AS
SIGNORS TO RODERICK LEAN MFG. CO., OF MANSFIELD, OHIO.

CULTIVATOR.

No. 821,235.

Specification of Letters Patent.

Patented May 22, 1906.

Application filed June 27, 1905. Serial No. 267,272.

To all whom it may concern:

Be it known that we, GEORGE W. Goss and CHARLES E. Goss, citizens of the United States, residing at Baltimore, in the county of Fairfield and State of Ohio, have invented a new and useful Cultivator, of which the following is a specification.

This invention relates to riding-cultivators; and among the objects of the invention are to 10 simplify and generally to improve the construction and operation of this class of devices.

With these and other ends in view, which will readily appear as the nature of the invention is better understood, the same consists in the improved construction and novel arrangement and combination of parts, which will be hereinafter fully described, and particularly pointed out in the claims.

20 In the accompanying drawings has been illustrated a simple and preferred form of the invention, it being, however, understood that no limitation is necessarily made to the precise structural details therein exhibited, but 25 that the right is reserved to any changes, alterations, and modifications to which recourse may be had within the scope of the invention and without departing from the spirit or sacrificing the efficiency of the same.

30 In said drawings, Figure 1 is a perspective front view of a cultivator constructed in accordance with the principles of the invention. Fig. 2 is a detail view, enlarged, in sectional elevation. Fig. 3 is a detail rear elevation. Fig. 4 is a detail plan view. Fig. 5 is a detail 35 view of the axle-adjusting means. Fig. 6 is a detail view of the gang-supporting means. Fig. 7 is a perspective detail view of the foot-lever frame and the handle-crank connected therewith. Fig. 8 is a sectional detail view 40 of one of the gang-supporting wheels or rollers.

45 Corresponding parts in the several figures are indicated throughout by similar characters of reference.

The frame of the improved cultivator includes a rear member 1, which preferably consists of a bar of channel-iron or steel of suitable dimensions. The side members of 50 the frame have been shown as being composed each of an upper and a lower bar 2 2', the rear ends of which are connected with the ends of the rear member 1, as by means of vertical bolts 3. The front of the frame is

likewise composed of an upper bar 4 and a 55 lower bar 4', here shown as angle-bars, and the ends of which are connected with the front ends of the side bars 2 2' by means of vertical bolt members 5, spacing tubes or sleeves 6 being mounted upon the said bolts 60 for the purpose of properly spacing the upper and lower frame members. The side members 2 and 2' are connected intermediate their ends by bolt members 7 and spacing-sleeves 8. The bolts 7 also serve to connect 65 the sides of the frame with cross-bars 9 and 10, the former of which is supported upon the upper end members 2 2 and is constructed of round, preferably tubular, iron, while the cross-bar 10, which has been shown as a flat 70 strap, is supported upon the lower end members 2' beneath the spacing-sleeves 8. A very simple and durable, approximately rectangular, frame is thus constructed, which is specially adapted to contain the gangs and 75 operating mechanism which is to be herein-after described.

Upon the front side of the rear or main-frame member 1 near the ends of said frame member are provided bearings 11 and 11', in 80 which are journaled a pair of stub-axles 12, one at each end, said axles having cranks 13, terminating in spindles 14, upon which the carrying-wheels 15 are supported for rotation. Upon the inner bearings 11 are mounted 85 clip members or plates 16, having depending lugs 17, each adapted to engage one of a plurality of segmental recesses 18 in the stub-axles, thus providing for the lateral adjustment of the latter, so that the gage of the machine may be regulated according to the distance that the rows of plants which are to be operated upon are apart from each other. It is obvious that such adjustment may be very easily effected by temporarily loosening or 90 detaching the plates 16, which are retained in operative position by screws 18 or other suitable means.

The lower end members 2' of the frame support rack-segments 19 concentrically, 100 upon which are pivoted hand-levers 20, having stops 21, whereby they may be retained in adjusted position. Said levers are connected, by means of link-rods 22, with collars or clamping members 23 upon the spindles 14. 105

It will be seen that by manipulating the levers 20 the stub-axles may be rocked and adjusted so as to adjust the ends of the car-

rying-frame vertically and independently of each other. In the drawings the lower ends of the levers 20 have been shown as being bifurcated, so as to embrace the rack-segments. 5 This construction is preferred; but it is not essential.

The implement herein shown is adapted to be drawn by three horses walking abreast, and it is therefore provided with two tongues 10 24, the rear ends of which extend between the front frame members 4 and 4' and between the cross-bars 9 and 10, being secured between the latter by means of bolts 25. Near the ends of the frame are obliquely-disposed braces 26, the forward ends of which 15 are secured upon the bolts 5 at the front corners of the frame, while the rear ends of said braces are secured upon the bolts 25. The braces 26 are reinforced by auxiliary braces 20 27, the rear ends of which are secured upon the bolts 7, whereby the upper and lower side bars of the frame are intermediately connected. The front ends of the braces 27 are connected with the braces 26 by means of bolts 28, which also form fulcrums for the 25 equalizers 29. At the upper front corners of the frame are hooks 30, upon which are suspended draft-bars 31, carrying the outer swingletrees 32. Said draft-bars are connected, by means of links 33, with the outer 30 ends of the equalizers. The inner ends of the equalizers are connected, by means of links 34, with the arms 35 of a bifurcated member 36, carrying at its lower end a middle swingletree 37.

35 The seat-supporting bar of the device has been shown as comprising two members 38 and 39, here shown as constructed of half-round iron, the upper member being supported upon the rear channel-bar 1 and extending beneath the cross-bar 9 and the front frame-bar 4, while the lower member 39 extends beneath the rear channel-bar 1 and the front frame-bar 4', the cross-bar 10 having a 40 central or intermediate dipped portion which extends beneath the member 39 to assist in supporting the latter. The arms of the bifurcated swingletree-supporting member 36 are pivoted upon a bolt or pin 40, extending 45 through the upper seat-bar member 38 near the front end of the latter. Said upper seat-bar member is bent downwardly in rear of the channel-bar 1 and is connected with the lower member 39, with which it contacts 50 by means including a clip 41, supporting the seat 42.

Upon the upper front frame member 4 are suitably supported clips 43, with which are pivotally connected rearwardly-extending 55 bars 44, having downturned rear ends 45 which extend through collars or bearings upon a laterally-slidable bar 46, which is supported in rear of the channel-bar 1 as by means of keys or pins 47, passing through 60 the members 45. The collars or bearings,

which are designated 48, are firmly supported upon or connected with the slide-bar 46. Upon the bars 44 are journaled wheels 49, which travel upon the upper side of the channel-bar 1. The slide-bar 46 is provided with 70 depending bracket members 50, in which are journaled rollers 51, bearing upon the under side of the channel-bar, which latter thus not only serves as a guide or track for the respective wheels and rollers, but also to prevent upward or downward displacement of the slide-bar 46.

The front frame members 4 and 4' are spaced apart at various places intermediate the ends thereof by means of spacing-sleeves 80 52, through which extend connecting-bolts 53. The sleeves 52 afford bearings for clip-plates 54, which consist simply of bent plates U-shaped in cross-section and having their free ends connected by bolts 55, upon which 85 are mounted the front ends of the beams 56 of the individual cultivator-gangs 57, which latter are of ordinary construction, being provided with standards 58 and earth-engaging blades 59 of the ordinary or any well-known 90 or approved construction.

The laterally-slidable bar 46 is provided with bearings 60 for the outer ends of rock-shafts 61, the inner ends of which have bearings in rack-segments 62 and 63, which are 95 likewise secured upon and extended upwardly from the sliding bar 46. The rock-shafts 61 are provided at their outer ends with cranks 63', which are connected, by means of link-rods 64, with the outer members of the cultivator-gangs, said members being provided with plates 65, through which said link-rods extend, the latter being provided beneath said plates with means, such as nuts 66, to enable them to be utilized for lifting the 100 members of the gangs. The rock-shafts have hand-levers 67 fixed thereupon, as by means of set-screws 68, and provided with stops 69, adapted to engage the rack-segments 62. Pivoted loosely upon the rock-shafts near the 105 inner ends of the latter are levers 70, having stop members 71, engaging the rack-segments 63. Said levers are provided with arms 72, connected by link-rods 73 with the inner members of the cultivator-gangs, which 110 are provided with plates 74 for the passage of the link-rods, which are provided with means, such as nuts 66^a, to prevent their withdrawal. The link-rods 64 and 73 are provided with stops 74', between which and the gang members are disposed coiled springs 115 75, exercising pressure in a downward direction and tending to hold the gangs in operative engagement with the ground when the device is in operation. It will be seen that 120 by means of the levers 67 and 70 and related parts the outer and inner members G and G' of the cultivator-gangs are capable of being independently adjusted vertically.

The laterally-slidable bar 46 is provided 125

with downwardly-extending arms 75' and 76, the outer ones of which, 75', are slidably connected with the outer members G of the cultivator-gangs, while the inner arms 76 are in like manner slidably connected with the inner members of the cultivator-gangs G'. The arms 75' and 76 are connected adjustably with the slide-bar 46 by means of clips, as 77, which will admit of said arms being suitably spaced apart, so as to regulate the distance between the cultivator-gangs and the individual members thereof, thus enabling the machine to be very readily adapted to operate upon corn or other plants planted various distances apart. A pivotal bolt 78, which extends vertically through the seat-bar members 38 and 39, constitutes a fulcrum, upon which is pivotally mounted a lever-frame 79, having two depending members 80 spaced apart by means of a brace 81, through which the pivotal bolt 78 extends, each of the members 80 being provided at its lower end with a foot-piece or treadle 82. The upper end of the lever-frame 79 has a rearward-extending arm 83, securely connected therewith and provided with a handle 84. The arm 83 is connected, by means of a link-rod 85, with an eye 86, formed upon one of the sleeves or collars 48, connected with the slide-bar 46. It will be seen that by manipulating the hand and foot levers, which may be done simultaneously by the operator, who is seated in a convenient position in rear of the foot-lever, the slide-bar 46, with all its related parts, will be moved laterally in either direction, thus providing for the lateral adjustment not only of the members of the cultivator-gangs, but also of the means whereby said gangs are manipulated or adjusted to their various positions.

The wheels 49, which travel upon the upper side of the channel-bar of the frame, are preferably of the construction illustrated in detail in Fig. 8 of the drawings, by reference to which it will be seen that said wheels have hubs 87, between which and the bars 44 are interposed antifriction-rollers 88, which are retained by means of washer-plates 89, adjacent to the hubs, said washer-plates being retained in position by means, such as cotter-pins 90.

From the foregoing description, taken in connection with the drawings hereto annexed, the operation and advantages of this invention will be readily understood by those skilled in the art to which it appertains. It has been endeavored to provide a separate and thoroughly-serviceable frame of light and durable construction and well adapted to support the cultivator-gangs and the adjusting and operating mechanism for said gangs. The ends of the gang-carrying frame are capable of independent vertical adjustment, which is desirable under many circumstances. Means are also provided whereby

not only the gangs but the individual members of said gangs may be adjusted transversely, so as to provide for any variation in the distance between the rows. It will further be observed that the inner and outer members of the gangs are capable of independent vertical adjustment, which is obviously desirable. The members of the gangs, which have been designated, respectively, as the "inner" and the "outer" members, 75 may obviously be interchanged when desired, according to the character of the work to be performed.

Having thus described the invention, what is claimed is—

1. A cultivator-frame including upper and lower front members extending transversely of the frame and bolts connecting said members, in combination with couplings engaging the bolts and cultivator members connected with the couplings. 80
2. A cultivator-frame including upper and lower front members and bolts connecting said members, in combination with cultivator members connected for universal movement with said connecting-bolts. 90
3. A cultivator-frame including upper and lower front members, bolts connecting said members, spacing-sleeves upon said bolts, and clips pivotally engaging the spacing-sleeves; in combination with cultivator-beams connected pivotally with said clips. 95
4. A cultivator-frame including upper and lower front members, bolts connecting said members, spacing-sleeves upon said bolts, and clips pivotally engaging the spacing-sleeves; in combination with cultivator-gang-members having beams connected pivotally with the pivoted clips, and means for effecting vertical and lateral adjustment of the gang members. 100

5. A cultivator-frame including a rear bar and upper and lower side and front members suitably connected and spaced apart, bars connected pivotally with the upper front members and having depending rear ends, wheels supported for rotation upon said bars and traveling upon the upper side of the rear member of the frame, and a laterally-movable slide-bar connected with and supported by the pendent rear ends of said pivoted bars. 110

6. A cultivator-frame, bars connected pivotally with the front of the frame and having pendent rear ends, rollers upon said bars traveling upon the rear frame-beam, a slide-bar connected with and supported by the pendent rear ends of the pivoted bars, cultivator-gang members having beams connected pivotally with the front of the frame, arms connected adjustably with the slide-bar and having sliding engagement with the cultivator-gangs, and means for effecting lateral adjustment of the slide-bar. 120

7. A cultivator-frame, bars pivoted upon the front of said frame and having rollers en- 130

- 4
- gaging the rear frame-bar, a slide-bar connected with and supported by the rear ends of the pivoted bars, and rollers supported by the slide-bar and engaging the under side of the rear frame-bar.
- 5 8. A cultivator-frame, bars pivoted upon the front member of said frame and having rotary members engaging the rear frame-bar, a slide-bar connected with and supported by 40 said pivoted bars, cultivator-gang members disconnected with the front frame-bar, arms depending from the slide-bar and having slide- 45 able engagement with said cultivator-gangs, and means connected with and supported by 15 the slide-bar for effecting vertical adjustment of the cultivator-gangs.
9. A cultivator-frame, bars connected pivotally with the front of the frame and having rotary members engaging the upper side of 20 the rear frame-bar, a slide-bar connected with and supported by said pivoted bars, means for preventing displacement in an upward direction of said frame-bar, cultivator-gangs connected with the front of the frame, means 25 connected with the slide-bar to prevent lateral displacement of the cultivator-gangs, and means connected with and supported by the slide-bar for effecting vertical adjustment of the cultivator-gangs.
- 30 10. A cultivator-frame, bars pivoted upon the front of said frame and having rotary members engaging the upper side of the rear frame-bar, a slide-bar connected with and supported by said pivoted bars, cultivator-gang members connected with the front frame- 35 bar, rock-shafts supported in bearings upon the slide-bar and having cranks at the outer ends, link-rods connecting said cranks with
- the outer gang members, adjusting-levers connected with said rock-shafts to operate 40 the latter, auxiliary levers fulcrumed upon said rock-shafts and having extending arms, links connecting said lever-arms with the inner gang members, and means for retaining the several adjusting-levers at various ad- 45 justments.
11. A cultivator-frame, a slide-bar supported for lateral movement with relation to the rear frame-bar, means for preventing upward displacement of said slide-bar, cultivator-gangs connected with the frame, adjust- 50 ing means for said gangs connected with the slide-bar, and means for effecting lateral ad- justment of the latter.
12. A cultivator-frame, a slide-bar sup- 55 ported for lateral movement with relation to the rear frame-bar, means for preventing upward displacement of said slide-bar, cultivator-gangs connected with the frame, adjust- 60 ing means for said gangs connected with and supported by the slide-bar, a seat-supporting bar, a lever-frame fulcrumed for movement in a horizontal plane upon said seat-bar and having depending members provided with treads, an arm extending laterally from 65 said lever-frame, and a link connecting said arm with the slide-bar to effect lateral adjust- ment of the latter.
- In testimony that we claim the foregoing as our own we have hereto affixed our signa- 70 tures in the presence of two witnesses.
